PAUL PASCHEN, OF NUERMBERG, GERMANY, ASSIGNOR TO WESTINGHOUSE ELECTRIC & MANUFACTURING COMPANY, A CORPORATION OF PENNSYLVANIA

REGULATOR SYSTEM

Application filed November 12, 1930, Serial No. 495,102, and in Germany November 13, 1929.

My invention relates to regulator systems and it has particular relation to systems for regulating electrical quantities, such as voltages of an electric circuit.

In certain applications, such, for example as where loads connected to a power circuit are of such character that the current required may vary over a wide range, the voltage may vary considerably from the desired value, and such changes may exist for varying periods of time. These variations in voltage may be only temporary and, if a regulator responds too quickly to such variations, a "pumping action" may cause the variations in voltage to become greater.

It is desirable that regulating systems of the character noted above shall have such degree of inertia that they will not be sensitive to very small temporary variations in the regulated quantity from the desired value, so that the regulator will not operate in response to each short-time voltage variation.

One object of my invention is to provide a regulator system for regulating an electrical quantity of a power circuit which shall not be immediately responsive to variations in the regulated quantity from the desired value.

Another object of my invention is to provide a regulator system for regulating an electrical quantity of a power circuit that will be responsive to variations in the quantity to be regulated in case such variations persist for a predetermined time but which will not be responsive to variations of short duration.

My invention will be better understood from the following description, when read in conjunction with the accompanying drawing, in which the single figure is a diagrammatic view of apparatus and circuits constituting a preferred embodiment of my invention.

Referring to the drawing, a regulating device 2, is provided for regulating the voltage of an electric circuit comprising conductors 3 and 4. The regulating device 2

comprises a resistor element 5 that is connected in series-circuit relation to the conductors 3 and 4 and a movable contact arm 6 that is actuated in the one direction by an electromagnet 11, a ratchet wheel 7, an armature lever 9 and a pawl 8, and in the other direction by an electromagnet 15, a ratchet wheel 12, an armature lever 14 and a pawl 13. A spring 16 is provided to bias the armature levers 9 and 14 toward their illustrated 50 55 positions.

The operating winding of the electromagnet 11 is energized from any convenient source, such as a battery 17, upon the closure of a switch 18. The switch 18 is operated to its circuit-closing position by an arm 19 that is actuated, through a shaft 21, by a differential device or mechanism 22 comprising three rotatable members 23, 24 and 25, the member 25 being differentially related to the members 23 and 24 and being connected to the shaft 21.

The member 23 of the differential device is driven, through a pinion 26, a shaft 27 and gear wheels 28, by means of a rotating device 29, that is energized from conductors 31 and 32 which are connected to the circuit conductors 3 and 4. The rotating device 29 may be of any well known type of rotating meter that is characterized by the fact 70 75 that its speed is a function of the quantity such as voltage, to be regulated. The rotating device 29 is provided with a braking or damping magnet 33 that may be adjusted to regulate its speed.

The member 24 of the differential device is driven, through a pinion 34, a shaft 35 and gear wheels 36, by any suitable constant-speed rotating device 37, which may also be energized from the conductors 31 and 32.

The energizing circuit for the rotating device 29 is completed through normally bridged contact members 38 of a relay 39, the operating winding of which is connected in series-circuit with the winding of the elec- 85 90

tromagnet 11 of the regulator 2. A dash pot 41 is associated with the relay 39 to give it a time-delay characteristic.

The energizing circuit for the rotating device 29 extends from the conductor 32, through conductor 42, the operating winding 42a of the device, conductor 43, the contact members 38 of relay 39 and conductor 44, to the conductor 31.

10 The operating winding of the electromagnet 15, is also energized from the battery 17, upon the actuation of a switch 46 to circuit-closing position by an arm 47 that is actuated, through a shaft 48 by a second differential device or mechanism 49. The differential device 49 comprises three rotatable members 51, 52 and 53, the member 53 being differentially related to the members 51 and 52 and being connected to the shafts 48.

20 The member 51 of the differential device 49 is driven, through a pinion 54, a shaft 55 and gear wheels 56 by means of a constant-speed rotating device 57 that is energized from the conductors 31 and 32.

25 The member 52 of the differential device 49 is driven, through a pinion 58, a shaft 59 and gear wheels 60, by means of a rotating device 62 that is energized from the conductors 31 and 32, its speed being a function of 30 the quantity to be regulated. A braking or damping magnet 63 is provided for the rotating device 62 and is adjustable to permit the speed of the rotating device 62 to be easily regulated.

35 The energizing circuit for the constant-speed rotating device 57 is completed through normally bridged contact members 65 of a relay 66, the operating winding of which is connected in the operating circuit of 40 the electromagnet 15 of the regulator 2. A dash-pot 67 is associated with the relay 66, to give it a time-delay characteristic.

The energizing circuit for the rotating device 57 extends from the conductor 32, through conductor 71, the operating winding 71a of the device, conductor 72, the contact members 65 of the relay 66 and the conductor 73, to the conductor 31.

The operation of my system is as follows: 50 When the voltage across the conductors 3 and 4 is at the desired value, all the rotating devices are operating at the same speed. The member 25 of the differential device 22 is stationary, and the arm 19 is pressed against 55 a stop 75 with a certain pressure, depending upon the sensitivity of the rotating device 37. The member 53 of the differential device 49 is also stationary, and the arm 47 is held against a stop 76 with a certain pressure, depending 60 upon the sensitivity of the rotating device 62.

In case the voltage of the circuit conductors 3 and 4 increases above a predetermined value, the speed of the rotating device 29 will be greater than that of the rotating device 37; thereby effecting movement of the

member 25 of the differential device 22 to actuate the arm 19 in a direction to close the switch 18. The closure of the switch 18 completes the operating circuit for the electromagnet 11, thereby actuating the ratchet wheel 7 to increase the resistance in circuit with the conductors 3 and 4 and to reduce the voltage thereof.

70 The operating circuit for the electromagnet 11 extends from one side of the battery 17, through conductor 78, conductor 79, the switch 18, conductor 80, the operating winding of the relay 39, conductor 81, the operating winding of the electromagnet 11, conductor 82 and conductor 83, to the other side 80 of the battery.

The energization of the operating winding of the relay 39, simultaneously with the energization of the electromagnet 11, effects the operation of the relay 39 and, after a 85 certain time delay, depending upon the adjustment of the dash-pot 41, the above traced circuit for the rotating device 29 is interrupted, causing the rotating device to slow down and stop. As the greater torque is 90 exerted by the rotating device 37, the arm 19 moves out of engagement with the switch 18, thereby allowing the relay 39 to close to complete the circuit for operating the rotating device 29.

95 If the single step of the regulator is not sufficient to effect the required correction, the electromagnet 11 will be again energized, and the arm 6 will be moved another step, as hereinbefore described, and step-by-step corrections will be continued until the required correction is effected.

In case the voltage of the circuit conductors 3 and 4 decreases below the predetermined value, the speed of the rotating device 62 is reduced, thus effecting movement of the member 53 of the differential device 49 to actuate the arm 47 in a direction to close the switch 46. Upon the closure of the switch 46, a circuit is completed for energizing the operating winding of the electromagnet 15, thereby actuating the ratchet wheel 12 and the arm 6 in a direction opposite to that described upon the energization of the electromagnet 11. The operation of the arm 6 decreases the resistance of the circuits 3 and 4 and increases the voltage thereof.

100 The operating circuit for the electromagnet 15, may be traced from the one side of the battery 17, through conductor 78, conductor 85, the switch 46, conductor 86, the operating winding of relay 66, conductor 87, the operating winding of the electromagnet 15, conductor 88 and conductor 83, to the other side 105 of the battery. The energization of the operating winding of the relay 66 actuates the relay and, after a certain time delay, depending upon the adjustment of the dash-pot 67, 110 interrupts the above traced operating circuit for the rotating device 57. The rotating de- 115

vice 62, operating alone, effects movement of the member 53, of the differential device 49 in such direction as to move the arm 47 out of engagement with the switch 46.

5 If the operation of the regulator 2 is not sufficient to increase the voltage of the circuit conductors 3 and 4 to the predetermined value, the arm 47 is again moved in a direction to effect the closure of the 10 switch 46, and the above described operation is repeated.

The movement of the arms 19 and 47 from the circuit-closing to the circuit-opening positions is effected by the momentary deenergization of the rotating devices 29 and 57, respectively, as hereinbefore described. It is obvious that several other ways of accomplishing this result may be employed, such as disconnecting the shafts 21 and 48 from 20 their associated differential devices, and effecting a return movement of the arms by any well known method.

The quickness of response of the regulating systems to a variation in the voltage of the circuit conductors 3 and 4, or, in other words, the system inertia may be adjusted by varying the distance between the switches 18 and 46 and their associated stop plugs 75 and 76. The sensitivity of the regulator 30 system may be adjusted by varying the torque or the speed of the rotating devices.

Since many modifications may be made in the details of my invention without departing from the spirit thereof, I do not wish 35 to be limited otherwise than by the scope of the appended claims.

I claim as my invention:

1. In a regulator system, in combination, 40 an electric circuit, regulator means connected to said circuit for varying an electrical quantity thereof, electro-responsive means for operating the regulator means in the one direction and a second electro-responsive means for operating the regulator means in the 45 other direction, contact-making means for controlling the energization of each of said electro-responsive means, a differential mechanism for actuating each contact-making means in accordance with an electrical quantity of said circuit.

2. In a regulator system, in combination, 55 an electric circuit, regulator means connected to said circuit for varying an electrical quantity thereof, electro-responsive means for operating the regulator means in the one direction and a second electro-responsive means for operating the regulator means in the other direction, contact-making means for controlling the energization of each of 60 said electro-responsive means, a differential mechanism for actuating each contact making means, one portion of each differential mechanism being rotated at a constant speed and the other portion being rotated in accordance with the quantity to be regulated.

3. In a regulator system, in combination, 70 an electric circuit, regulator means connected to said circuit for varying an electrical quantity thereof, electro-responsive means for operating the regulator means in the one direction and a second electro-responsive means for operating the regulator means in the other direction, contact-making means for controlling the energization of each of said 75 electro-responsive means, a differential mechanism for actuating each contact-making means, one portion of each differential mechanism being actuated by a rotating device operating at constant speed and the other portion being actuated by a rotating device 80 the speed of which is a function of an electrical quantity of said circuit.

4. In a regulator system, in combination, 85 an electric circuit, regulator means connected to said circuit for varying an electrical quantity thereof, electro-responsive means for operating the regulator means in the one direction and a second electro-responsive means for operating the regulator in the other direction, contact-making means for controlling the energization of each of said 90 electro-responsive means, a differential mechanism for actuating each contact-making means, one portion of each differential mechanism being actuated by a rotating device operating at constant speed and the other portion being actuated by a rotating device the speed of which is a function of an electrical quantity of said circuit, and means for interrupting the circuit of the rotating device, 95 when operating at the higher speed, upon the operation of the regulator in one direction to effect the return of the actuated differential mechanism to a neutral position.

5. In a regulator system, in combination, 105 an electric circuit, regulator means connected thereto for regulating an electrical quantity thereof, electro-responsive means for operating the regulating means in the one direction and a second electro-responsive means for operating the regulating means in the other direction, contact-making means for controlling the energization of each electro-responsive means, a contact arm for actuating each contact-making means, a differential device for actuating each contact arm, said differential devices being responsive to the difference in speeds of a constant-speed device and a device the speed of which is a function of the quantity to be regulated.

6. In a regulator system, in combination, 115 an electric circuit, regulator means connected thereto for regulating an electrical quantity thereof, electro-responsive means for operating the regulating means in the one direction and a second electro-responsive means for operating the regulating means in the other direction, contact-making means for controlling the energization of each electro-responsive means, a contact arm for actuating 120
